LUMINAIRE

Edwin F. Guth, Jr., Ladue, Mo., assignor to The Edwin F. Guth Company, St. Louis, Mo., a corporation of Missouri

Filed June 16, 1960, Ser. No. 60,996

Term of patent 14 years

(Cl. D48—23)

FIG.1

The panel member has conventional rectangular shaped openings.

I claim:

The ornamental design for a luminaire, as shown and described.
